Primary Examiner — Jennifer Rivard(57) **CLAIM**

The ornamental design for a razor handle extension, as shown and described.

DESCRIPTION

FIG. 1 is an isometric view of the razor handle extension embodying our new design;

FIG. 2 is a front end view of razor handle extension;

FIG. 3 is a back end view of the razor handle extension;

FIG. 4 is a right side view of the razor handle extension;

FIG. 5 is a left side view of the razor handle extension;

FIG. 6 is a top view of the razor handle extension;

FIG. 7 is a bottom view of the razor handle extension;

FIG. 8 is an alternate isometric view of the razor handle extension;

FIG. 9 is an environmental view of the razor handle extension; and,

FIG. 10 is a perspective view of an alternate embodiment of the razor handle extension.

The broken lines in FIGS. 1-8 and 10 illustrate portions of the razor handle extension. The broken lines in FIG. 9 illustrate the environment. None of the broken lines forms part of the claimed design.
